TENNIS SCORING DEVICE

Ralph Herbert Paul, Cremorne, Sydney,
New South Wales, Australia

Application March 23, 1938, Serial No. 197,723

10 Claims. (Cl. 235—115)

This invention relates to a scoring device and particularly to a device for registering the scores in the game of lawn tennis, and it consists in the constructions, arrangements and combinations 5 herein described and claimed.

In registering a score in the game of lawn tennis from "love all" position, 15 is called when a side wins its first point; 30 when the side wins its second point, and 40 when the side wins its 10 third point. The scoring is peculiar, however, for when both sides have each won the three points out of the first six won, the score instead of being called 40 all is called "deuce" and from this position, one of the sides has to win two 15 consecutive points before that side wins the game (long game). From a "deuce" position the winning of an intermediate point by either side is called "advantage" and should the side with "advantage" fail to win the next point, the score again returns to "deuce". It will be seen that 20 where one side has "advantage" the other side must win three points at least, to win the game. Should, however, a side win four points, before the other side has won three points, it wins the 25 game (short game) and the position of "deuce" is not arrived at. In the case of the handicap game, one or both of the sides may owe points, for example, one side may owe 40 against 30, in which case the former side must win three points 30 and the latter side two points, before reaching "love" position.

Therefore, a game scoring device suitable for registering the scores of lawn tennis must have two scoring members, one for each side, and there 35 must be cooperation between such members at and after the "deuce" position so that a registering movement to "advantage" position of either one of the members, reverses the other member to show a blank in the respective window, and in 40 fact, the two scoring members oscillate together between a score of "advantage" to one side and "advantage" to the other side. Also a registering movement from "advantage" to "game" further reverses the other member, and means must 45 also be provided for a different series of score indications on the scoring members to be displayed when each side has won three points out of the first six won from a "love" position.

50 It is therefore an object of the invention to provide a novel and compact scoring device for use by umpires and having means for carrying out the above score registering means.

Additional objects, advantages and features of 55 invention will be apparent from the following de-

scription considered in conjunction with the accompanying drawings, wherein—

Figure 1 is a plan view of my scoring device.

Figure 2 is a similar view with the cover and team indicator slide removed. 5

Figures 3 to 5 illustrate positions of the scoring device at various points of a game.

Figure 6 is a cross section on the line 6—6 of Figure 1.

Figure 7 is a plan view of an element of the 10 scoring device.

Figure 8 is a similar view of a control member of the device.

Figure 9 is a detail of a spring employed in the 15 device.

Figure 10 is an enlarged plan view of one of the scoring members.

Figure 11 is a perspective view of a pivot pin.

Figure 12 is a plan view of a game scoring disc.

Figure 13 is a detail perspective view of a team 20 indicator slide employed with the device.

In carrying out the invention, I provide a base plate 10 centrally of which there is provided an annular recess 11, in which a pair of segmental scoring members 12 and 13 are disposed. The 25 scoring members 12—13 snugly fit within the recess 11 for rotatable movement therein and lie slightly below the upper face of the base 10, and housed by a cover plate 14, the latter having in its lower portion arcuate slots 15 and 16 subtending 30 10 degrees at the center adapted to register with a multiplicity of apertures 17 of the respective scoring members, the apertures also being spaced 10 degrees apart and arranged circumferentially of the scoring members 12—13. The 35 slots 15—16 permit insertion of a pointed instrument to engage an aperture 17 of a respective scoring member to register the points won by a side. The cover plate 14 also has two concentric slots 18 and 19 arranged in an upper portion 40 thereof positioned on the same radial axis as the slots 15—16, and subtending 50 degrees at the center. These slots permit the insertion of a pointed instrument so as to engage an aperture 45 17 of the scoring members for the setting of the members at the start of a game, by rotating the scoring members in directions reverse to those when registering points.

Each of the scoring members 12 are provided with identical scoring indicia, i. e., "Game"; 50 "Van"; "40"; "Deuce"; "30"; "15"; "Love"; and between the "love" and "15" position and the "15" and "30" position suitably colored blank portions are provided. Below the "love" position we find notations such as "Owe 15"; "Owe 30"; 55

and "Owe 40", and these latter are preferably colored red. (See Fig. 10.) The scoring indicia referred to will be displayed through respective windows 29-21 of the cover plate 14, so as to show the individual score of each side.

Each of the scoring members 12-13 includes an arcuate rib 22 arranged upon its outer periphery which function as cam members in certain movements of the scoring members, as will be described more fully hereinafter, and each scoring member 12-13 includes spaced notches 23 about their peripheries cooperable with respective spring detents 24 for maintaining the scoring devices in a set position. If desired, an additional spring detent 25 may be positioned upon the inner periphery of the scoring members, as shown in Figure 2.

Each scoring member 12-13 also has an arcuate slot 26 adjacent their inner peripheries positioned so as to be aligned in particular positions of their movements for a purpose presently to be explained.

The formation of the annular recess 11 in the base provides a central disk portion 27 in a lower portion of which there is formed a recess 28 housing a bowed leaf-spring 29 cooperable with a bill portion 30 of a slide 31.

The slide 31 is substantially arcuate shaped defined by oppositely extended arms 32-33 adjacent the upper ends of which are provided windows 34-35 adapted to register with respective windows 20-21 of the cover 14. The bill portion 30 is carried by an upwardly extended medial arm 36 and a downwardly oppositely extended arm 37 is also provided. The arm 37 includes an offset portion 38 carrying a pivot pin 39 for mounting of a rocking lever 40.

The arm 36 includes a detent pin 41 cooperable with the slots 26 when the scoring members 12-13 are moved to certain positions.

The rocking lever 40 is of arcuate formation, the upper ends of which lie slightly inward of the outer periphery of the recess 11, normally, and each of the levers is provided with rabbeted portions 42 providing shoulders 43 and each end of the levers is provided with a cam face 42^a which cooperate with respective ribs 22 of the scoring members 12-13 when the latter are in certain positions. The rabbet 42 engages the adjacent lower ends of respective scoring members and locks the lever 40 against unrequired movement.

The cover plate 14 will be suitably recessed as at 43', to accommodate the slide 31 and the rocking lever 40 and the cover plate will also include windows 44 and arcuate slots 45 at upper and lower portions thereof for display of numbers imprinted upon respective rotatable disks 46, representing games won by the teams the slots 45 exposing suitable circumferentially spaced apertures 47 on the disks whereby to permit rotation thereof. Any suitable detent means may be employed for retaining the disks in a set position such as a spring 48, engaged in a peripheral notch of the disk (see Fig. 2).

Further, the cover plate 14 includes upper and lower windows 49 and 50 (see Fig. 1), the adjacent vertical edge being cut away as at 51, and the underside of the cover being suitably recessed to provide a pocket for reception of a score result card 52. The cards 52 will bear all necessary notations as to the games and sets won, handicap, etc., and in the present instance, the top score card 52 will represent opening service side.

As is well understood, during the playing of

each set, the teams must change and positions on the court on each occasion when the joint games won are odd in number and in order to register an accurate scoring of games won, means must be provided for registering these changes of position of the teams. Therefore, the cover plate 14 is provided with a horizontal slot 53 located medially of the cover and adjacent the ends of the slot, respective windows 54 and 55 are formed; and upon the base plate so as to register with the windows 54-55 there is printed the word "Bottom". A slide bar 56 is arranged within the slot 53 and has printed upon a face thereof the word "Top", the word located adjacent the respective ends of the bar, and the bar 56 has formed medially thereof an aperture 57 registering with the slot 53. As may be seen in Figure 1, the bar 56 may be shifted from one side to the other by engaging a stylus or pencil in the aperture 57. The printing on the base and the slide bar will be so located as to disclose "Top" in the window 54 and "Bottom" in the window 55, yet the slide may be moved to reverse the showing of the words, which would be done at the time that the teams change positions upon the court, and this identifies the game scoring disk to be actuated.

In use, in a non-handicap game, the scoring members 12 and 13 would be in positions so that the words "Love" would appear in the windows 20 and 21, the scoring member 12 being movable in a counter-clockwise direction and the member 13 in a clockwise direction to indicate the scores of the sides. We will assume that the "Top" team indicated in the window 54 is the server from the left hand court, and the slide 56 set accordingly, and has scored the first point which will necessitate movement of the scoring member 12 counter-clockwise, and this will be done by engaging a stylus in the aperture displayed through the slot 15 and pulling downward to lower end of the slot. The next point being won by the bottom team, movement of the scoring member 13 is similarly effected in a clockwise direction, to indicate the numeral "15" in the window 21. The movement of the scoring members is thus understood and we will now assume that the game has progressed to such extent that the top team has reached a score of "40" as shown in Figure 2 and the bottom team has a score of "30". It will be noted that the score member 12 has thus moved so that its lower end edge lies substantially in the vertical longitudinal axis of the arm 37 of the slide 31, with the rib 22 engaging the adjacent cam face 42^a, and this engagement will have caused the lever 49 to rock on its pivot 39 disposing the other end of the lever 40 so as to lie in the path of the rib 22 of the scoring member 13. Now, if the bottom team should score the next point, the scoring member 13 will be moved in clockwise direction and such movement, it will be noted, forcibly moves the rocking lever 40 downwardly, by reason of engagement of the rib 22 and the adjacent cam face of the lever, and the further locked engagement of the opposite end of the lever with the rib 22 of the scoring member 12. In this position, the scoring members 12-13 will occupy positions in the lower recess 11, with their ends abutting, the arcuate slots 26 aligned and the pin 49 in alignment with the slots; and the slide 31 drawn downwardly, compressing the spring 29. (See Fig. 5). The ends of the scoring members are in abutting relation and the downward movement of the slide 31 brings the windows 34 and 35 so as to cover the upper half and open up the 75

lower half of the sight windows 20 and 21 in the cover plate 14, thereby displaying another series of score indications on the scoring members 12 and 13. It is necessary that this lower position should be maintained until the finish of the game. The score would be even and the scoring members would display "Deuce—Deuce". Suppose now, the bottom team should win the next point. Clockwise movement of the member 13 would be effected with a stylus and since the end of the scoring member is in abutting engagement with the adjacent end of the member 12 anti-clockwise movement of the scoring member 12 will be effected, disclosing a blank colored portion in the window 20 and display of "Van" in the window 21, the slide 31 still being held in its lower position by reason of engagement of the pin 41 in the slot 25 in the member 13. The next point again being won by the bottom team, the member 13 is again moved and the word "Game" appears in the window 21. The game is registered on the lower score dial 46, as indicated by the slide member 56.

After a game has been won, the scoring members 12 and 13 are returned to their desired positions by inserting a stylus through respective slots 18 and 19 so as to engage an aperture of the scoring members, and moving them in reverse directions to those used when scoring points.

In the case of a handicap game, the team giving the handicap would have its scoring member set in the slot 18 or 19 as the case may be, to indicate the handicap, such as "Owe 15"; "Owe 30", in the respective window 20 or 21.

It will be obvious that when the scoring members oscillate from "advantage" on one side to "advantage" to the other side, the rocking lever 40 will be rocked alternately by the scoring members 12—13 owing to engagement with respective ribs 22.

It should be seen that at a "deuce" score the rabbeted portions 43 of the rocking lever contacting the ribs 22 of respective scoring members will prevent the return of the slide 31 to its normal position. It will be further seen that at the score of "advantage" owing to one of the scoring members having been pushed backward one end of the rocking levers is free of engagement with the rib 22, allowing rocking movement of the lever 40, thereby releasing the locking of the slide 31. The slide however, owing to the pin 39 having engaged in one of the slots 26 of the progressed scoring member holds the slide 31 in its required downward position taking up the duty of the previously locked rocking lever. Should the score revert to "deuce" the rocking lever again becomes locked and performs its required function in place of the pin.

From the foregoing, it will be seen that the slide 31 only comes into operation at the time that the scoring members 12—13 are about to contact (see Fig. 2), to effect downward sliding movement of the slide, and this downward movement of the slide windows has the same effect as the partial rotation of the scoring members, away from each other, which is essential in order to bring into operation a different series of score indicated and the score "deuce-deuce" rather than "40—40" and also the scores of "van" and "game", afterwards.

It should be noted that the inner lower ends of the scoring members 12 and 13 are slightly cut back as at 12a which when they are brought into end abutting relation provide an entrance slot for the pin 41, and in order that re-setting movement

of the scoring members 12 and 13 may be arrested, a lug 11a is provided in the recess 11.

While I have shown and described a preferred embodiment of the invention, this is by way of illustration only, and I consider as my own all such modifications in structure as fairly fall within the scope of the appended claims.

I claim:

1. A tennis scoring device comprising a face plate provided with sight openings, point scoring units movably mounted beneath the face plate and having scoring indicia thereon for display at certain of said sight openings, a slide member co-operable with the scoring units in their various positions of movement, and said slide having windows for registry with the sight openings.

2. A tennis scoring device comprising a face plate provided with sight openings, point scoring units movably mounted beneath the face plate and having scoring indicia thereon for display at certain of said sight openings, a slide member co-operable with the scoring units in their various positions of movement, said slide member having windows for registry with the sight openings of the face plate, and means between the scoring units and the slide for maintaining the windows of the slide in registry with the sight openings.

3. A tennis scoring device comprising a face plate provided with sight openings, point scoring members movably mounted beneath the face plate and having indicia thereon for display at the sight openings, a slide member interposed between the scoring members and the back wall of the face plate, said slide having windows for registry with respective sight openings of the face plate, means between respective scoring members and the slide member for registering a lower portion of the windows of the slide with sight openings when the score attained is "deuce", and said scoring members having means co-operable with the slide member for maintaining the windows and sight openings in registry.

4. A tennis scoring device comprising a base plate having an annular recess, a pair of annular segmental scoring members slidably disposed therein, each scoring member having scoring indicia thereon, a slide member disposed above the scoring members, a face plate having sight openings for display of scoring indicia of the scoring members, said slide having windows for registry with a lower portion of the sight openings when said scoring members have been moved to a "deuce" position and means between the slide and scoring members for retaining the slide in lowered position until released by resetting of the score members.

5. A tennis scoring device comprising a base plate having an annular recess, a pair of annular segmental scoring members slidably disposed therein, each scoring member having score indicia thereon, a slide member disposed above the scoring members, the slide having oppositely extended arms, each arm having a window aligned with the score indicia of the scoring members, a face plate having sight openings for display of scoring indicia of the scoring members, an arcuate rocking lever pivoted to the slide member, the ends of the lever having cam contact with the scoring members, whereby further sliding movement of one of the scoring members will cause said lever to rock to dispose an end of the lever into the path of the other scoring member, movement of the latter scoring member effecting downward movement of the slide for registry of a lower portion of the windows and sight openings when

- the game has progressed to a "deuce" position, and means between the slide and scoring members for retaining the slide in lowered position until released by resetting movement of the scoring members.
6. A tennis scoring device comprising a base plate having an annular recess, a pair of annular segmental scoring members circumferentially slidable therein, each scoring member having score indicia thereon, a face plate having sight openings for display of the score indicia, a slide member between the scoring members and the face plate, the slide having windows for registry with the sight openings, springs means for holding the slide in uppermost position, means between the slide and scoring members for retracting the slide when the score attained is at and after a "deuce" position, and detent means for holding the slide retracted until released by resetting of the scoring members.
7. A tennis scoring device comprising a base plate having an annular recess, a pair of annular segmental scoring members slidably disposed therein, each scoring member having score indicia thereon, a face plate having sight openings for display of the score indicia, a slide member between the scoring members and the face plate, the slide having windows of a depth approximately one-half that of the sight openings for alternate registry with the upper and lower portions of the sight openings, spring means for holding the slide in uppermost position, means between the slide and scoring members for retracting the slide when the score attained is at and after a "deuce" position, each scoring member having a slot opening upon its advance end and adapted to register at and after a "deuce" position, a pin on the slide positioned to enter either slot for holding the slide retracted until released by re-setting of the scoring members.
8. A tennis scoring device comprising a base plate having an annular recess, a pair of annular segmental scoring members slidably disposed therein, each scoring member having score indicia thereon and spaced apertures adjacent their outer peripheries, each scoring member further having spaced peripheral notches, a toothed spring member complementary to the notches of each score member, a face plate having sight openings for display of the score indicia, said face plate further having arcuate slots for registry with the apertures of the scoring members, a slide member disposed between the scoring members and the face plate, said slide having arms apertured to provide windows, said windows being of a depth approximately one-half of the sight openings, registered with the upper and lower portions of the sight openings, the slide further having medial upward and downward extensions, the upward extension having a bill portion, a leaf spring beneath the bill for holding the slide in uppermost position, an arcuate shaped lever rockably pivoted to the downward extension of the slide, the ends of the lever having cam faces, the inner edge of the lever having cut away portions defining a right-angularly disposed rib on each score member, said ribs being complementary to the cam face and shoulder of respective ends of the lever whereby to rock the lever into the path of the scoring members, movement of the scoring members to a "deuce" position retracting the slide against the action of the spring, each of said scoring members having an arcuate slot in its advancing end and adapted to register before and after "deuce" position of the scoring members; and a pin in the slide positioned to engage within the slots upon further movement of the scoring members from "deuce" position.
9. A tennis scoring device comprising a base plate having an annular recess, a pair of annular segmental scoring members slidably disposed therein, each scoring member having score indicia thereon and spaced apertures adjacent their outer peripheries each scoring member further having spaced peripheral notches, a toothed spring member complementary to the notches of each score member, a face plate having sight openings for display of the score indicia, said face plate further having arcuate slots for registry with the apertures of the scoring members, a slide member disposed between the scoring members and the face plate, said slide having arms apertured to provide windows, said windows being of a depth approximately one-half of the sight openings registered with the upper and lower portions of the sight openings, the slide further having medial upward and downward extensions, the upward extension having a bill portion, a leaf spring beneath the bill for holding the slide in uppermost position, an arcuate shaped lever rockably pivoted to the downward extension of the slide, the ends of the lever having cam faces, the inner edge of the lever having cut away portions defining a right-angularly disposed rib on each score member, said ribs being complementary to the cam face and shoulder of respective ends of the lever whereby to rock the lever into the path of the scoring members, movement of the scoring members to a "deuce" position retracting the slide against the action of the spring, each of said scoring members having an arcuate slot in its advancing end and adapted to register before and after "deuce" position of the scoring members; and a pin in the slide positioned to engage within the slots upon further movement of the scoring members from "deuce" position.
10. A tennis scoring device comprising a base plate having an annular recess, a pair of annular segmental scoring members slidably disposed therein, each scoring member having scoring indicia thereon, a slide member disposed above the scoring members, a face plate having sight openings for display of scoring indicia of the scoring members, said slide having windows for registry with a lower portion of the sight opening when said scoring members have been moved to bring adjacent ends into abutting relation whereby further forward movement of one of the scoring members will effect rearward movement of the other scoring member, and means between the slide and scoring members for retaining the slide in lowered position until released by a resetting of the score members.

RALPH HERBERT PAUL.
